UNITED STATES PATENT OFFICE

WILLIAM C. WILLETS, OF GLENDALE, CALIFORNIA

DESIGN FOR AN ICELESS COOLER

Application filed March 19, 1932. Serial No. 43,237. Term of patent 7 years.

To all whom it may concern:

Be it known that I, WILLIAM C. WILLETS, a citizen of the United States, residing at Glendale, in the county of Los Angeles and State of California, have invented a new, original, and ornamental Design for Iceless Coolers, of which the following is a specification, reference being had to the accompanying drawings, forming part thereof.

In the drawings, Fig. 1 is a front elevation of an iceless cooler embodying my design and Fig. 2 is a plan view.

I claim:

The ornamental design for an iceless cooler, as shown.

WILLIAM C. WILLETS.
